UNITED STATES PATENT OFFICE.

HARRY BRADWELL, OF KEIGHLEY, ENGLAND.

WRAPPING-MACHINE.

1,118,468.

Specification of Letters Patent.

Patented Nov. 24, 1914.

Application filed December 12, 1912. Serial No. 736,393.

To all whom it may concern:

Be it known that I, HARRY BRADWELL, a subject of the King of Great Britain, residing at Keighley, in the county of York, 5 England, have invented a new and useful Improvement in Wrapping-Machines, of which the following is a specification.

This invention relates to improvements in machines or apparatus for wrapping toffee, 10 caramels, chocolates, and other sweetmeats and the like articles in paper covers, the ends of which are to be twisted to retain them in position, and my present invention consists in the production of a new or improved machine or apparatus for this purpose.

According to my invention, the paper for wrapping purposes is first fed from a roll and a portion sufficient for the wrapping of 20 one article subsequently severed or cut off. The wrapper is suitably supported in position over a plate carried by a rod radially disposed in an intermittently rotated disk.

The article to be wrapped is supplied 25 from a magazine by being pressed through the outlet on to the wrapper and together with the wrapper into a recess or the like formed in the periphery of said disk, where it is held during the subsequent folding and 30 twisting operations. The pressing down of the article into said recess causes the free ends or sides of the wrapping paper to assume approximately vertical positions, when they are folded over the article by a cam 35 operated lever and by the disk on the next forward feed. This movement or feed of the disk is also such as to bring the article with the loose ends of the wrapper into a position opposite two pairs of twisting jaws 40 which subsequently seize and twist the said ends in the desired manner for effectually inclosing or parceling the article. The continued rotation of the parceling disk enables the package to be conveniently discharged 45 into a tray, conveyer or the like for removal.

The particular construction and arrangement of the mechanism and the movements necessary for performing the operations are such as to insure a continued and automatic 50 performance.

Description of drawings: Figure 1 is a plan view of my improved machine or apparatus for wrapping toffee, caramels, chocolates, and other sweetmeats and the like. 55 Fig. 2 is a sectional side elevation of part of apparatus shown at Fig. 1. Fig. 3 is a

side elevation of one section of feed mechanism shown at Fig. 1, and means for operating twisting jaws. Figs. 4 and 5 show plan and elevation of magazine and controlling means for feeding articles to be wrapped or parcelled. Fig. 6 is a sectional side elevation showing details of feed mechanism for supplying wrapping paper and for rotating the parceling disk. Fig. 7 is a sectional side elevation showing the means for operating sliding jaws in the parceling disk. Fig. 8 is a similar view showing article to be wrapped being held in disk during the withdrawal of plunger. Fig. 9 is a similar view showing means for effecting the first portion of the folding operation. Fig. 10 is also a similar view showing the folding operation completed. Figs. 11 and 12 are a plan view and an elevation showing the relative positions of article and its wrapper in the first stage of the wrapping operation. Fig. 13 shows the article and its wrapper after the completion of the second stage. Fig. 14 shows the position of wrapper at the end 80 of the third stage. Figs. 15 and 16 show an elevation and a plan view of article and its wrapper after the completion of the fourth stage and before the loose ends are twisted. Fig. 17 shows a plan view of the completed 85 package.

Similar letters and figures refer to similar parts throughout the several views.

In carrying this invention into effect, I employ suitable standards or supports A 90 suitably secured upon the machine table H, and mount therein a convenient shaft A¹ carrying a roller B having a gripping surface in connection with which operates another similar roller C mounted in resilient 95 bearings D so that it exercises a continuous pressure upon said roller B. The roller B projects through a slot B¹ in a feed table B² also carried by the standards A, with its periphery slightly above the surface of said table. Between these two rollers over the table B² is fed the paper E for wrapping purposes from a roll F which is placed in bearings G also secured to the table H or in any other convenient position in or in 100 proximity to the machine, such feeding of the paper being intermittently performed in order that the requisite amount of paper for wrapping one of the articles to be parcelled is fed forward to appropriate supports or 105 holders J, J. The feed is effected by a pinion K upon the shaft A¹, gear wheels L, L, 110

shaft M, ratchet N, ratchet wheel P, levers R, R, and connecting rod S, operated by the cam T on the main driving shaft U see Fig. 6. This paper on being fed forward 5 by the rollers B C, is automatically operated upon by a knife V mounted upon a shaft W movable in bearings in the standard A by lever X and cam Y, the latter also keyed on shaft U, by which means a portion thereof, sufficient for the wrapping of one article 10 is severed or cut off on the termination of each feed.

In suitable proximity to the parts J J, upon which the paper is fed, see Fig. 2, is 15 mounted the magazine for supplying the articles to be wrapped, which preferably consists of a fixed flanged disk or plate 1, and above or within this fixed plate and in close proximity thereto is arranged another 20 plate 2 having recesses, notches, or serrations 3 near or in its outer edge. This serrated plate is also intermittently moved sufficient to bring the next space or serration immediately over the outlet or chute 4 in 25 the plate 1. The plate 2 is mounted upon a flanged sleeve 5 fitting a vertical stud or shaft, and is given the necessary rotation by ratchet 7 pivoting upon a lever 8 operated by a cam 9 upon the shaft 10, actuating 30 the ratchet wheel 6. The number of articles to be wrapped are placed in position between or in these serrations to rest upon the fixed disk 1 below, and the number of teeth in the wheel 6 preferably corresponds 35 with the number of spaces in the wheel 2, so that the movement of said wheel 6 the space of one tooth is synonymous with the movement of the wheel 2 for feeding another article to the wrapping device hereinafter described. The shaft 10 is driven by 40 chain 11 and chain wheels 12 from the main shaft U.

As each article enters the chute it comes 45 in contact with and is held by suitable spring jaws 13 while the paper is moved into position and a portion cut off. The jaws are of separate construction secured to a bracket 13^A, and the lower jaw projects farther than the upper jaw in order to cope 50 with any unevenness in size of the article to be treated. When the paper wrapper has been cut off, a plunger or finger 14 secured to one end of a vertical shaft 15 sliding within a suitable bearing 16, is operated by 55 a spring 17, or by a cam actuated lever, to press each article through the outlet 4 on to the paper wrapper and together with the wrapper against a plate or head 18 carried by a piston or rod 19 operating between a 60 fixed jaw 20 and a sliding jaw 21 and radially disposed in a disk 22, which is intermittently rotated simultaneously with and by the shaft M aforesaid.

The sliding jaw 21 is controlled by a 65 spring 23 and held in open position in op-

position to said spring by a pivoted lever 24 which engages a cross head 21^A carried by the spindle 21^B at each side of the disk 22; said lever 24 is operated by cam 25 on shaft U during the time that the article is 70 being pressed down by the aforesaid plunger 14 but the jaw is allowed to close on said article in order to prevent it shifting its position on the withdrawal of the plunger by the lever 17^A and cam 17^B which act in 75 opposition to the spring 17, and to so hold the same during the subsequent folding and twisting operations, see Figs. 7 and 8. The wrapping paper at this stage will partially surround the article with the free sides extending somewhat in a vertical direction, 80 see also Fig. 13.

To fold the sides of the wrapper over the said article I employ a plate 26 mounted upon a pivoted lever 27 also operated by a 85 suitable cam 28 on shaft U. This plate see Fig. 9 lays one free side of the wrapper on the top of the article while the other side is folded to overlap this one, as shown at Figs. 15 and 16, by the next operation of 90 the disk 22. The disk 22 in being rotated an appropriate distance brings the unfolded portion of the wrapper against the edge of one of the plates J which turns it down as aforesaid, and it is so held by a spring plate 95 or cover J¹ during the rest of the feed movement of said disk and the subsequent twisting of the free ends of same. At the termination of the aforesaid feed the partially wrapped article is brought into a position 100 opposite two pairs of jaws or grippers which are capable of both rotary or oscillating movements and a movement longitudinally of their bearings.

Each pair of jaws or grippers 29 are fixed 105 upon a shaft 35 mounted in suitable bearings 35^B situated upon each side of the disk 22 and at right angles to the same; said jaws are automatically actuated in the direction for opening them by means of pivoted levers 30 operated by cams 31 on the shaft 10, while they are closed on the return of said levers, by the springs 32 or other suitable means. Their oscillating motions are preferably effected by means of quadrants 33 gearing with pinions 34 mounted 110 on the shafts 35 aforesaid, said quadrants being reciprocated in any appropriate manner such as by being mounted upon a common shaft or pivot 36 with an arm 37 operated by cam 38 on the shaft U, while their longitudinal movements are also effected from said shaft by cam 39 actuating levers or arms 40, 41 keyed to shaft 42, the end of lever 41 operating within a neck 43 upon each shaft 35. Their actions are such that on the disk 22 bringing the partially wrapped article to a position opposite these shafts 35, the latter, with the jaws opened 115 by the levers 30 as they are moved longitudinally 120 of their bearings.

The sliding jaw 21 is controlled by a 125 spring 23 and held in open position in op-

dinally of their bearings toward said article, are in such a position that the now open jaws surround or partially surround the ends of the wrapping paper, when said jaws 5 released by the springs 30^a acting on levers 30, are closed by the springs 32 and lay hold of the ends of said paper so that the rotation of the said shafts by the quadrants will twist said ends in the manner desired 10 for effectually retaining or inclosing the articles under treatment. The rotation of the shafts for twisting purposes occurs before the completion of the longitudinal movement, so that the latter may compensate 15 for the shortening of the package and prevent fracture of the wrapper during such twisting operation. Upon the completion of the twisting operation and immediately preceding the return of the shafts by the 20 levers 40, 41, actuated by the springs 35^c, the jaws are again opened to release the package by the cam projection 45 on the cams 31 operating on the levers 30. This release of the package occurs immediately 25 preceding the next operation of the disk 22.

Instead of transmitting oscillating motion to the shafts carrying the grippers as above described, I may transmit thereto intermittent rotary motion, and this latter 30 may, if desired, by appropriate gearing be obtained from any of the shafts in the machine which move intermittently, or ratchet and wheel, or other mechanism may be employed for this purpose.

35 The jaws are preferably provided with an india rubber or similar pad or lining 46 which enables them to more effectually lay hold of the ends of the wrapper, and all the cam operated levers are where necessary 40 turnable by springs, weights, or the like.

The continued rotation of the disk 22 carries the article or package underneath or to the lowest point in said disk where it is dislodged by a lever 47 actuated by a cam 48 45 upon the shaft 10, or by a fixed cam surface acting on said piston rod 19 sliding same in its bearings 49 formed by a swell on the side of the aforesaid disk, until the package is pressed out of the grip of the 50 jaw 21 when it may drop into an appropriate receptacle or upon a traveling belt, band or the like, so as to be packed or transferred to any part desired. The rod 19 is also controlled in its movement by the pressure of

55 a spring 50, or by other suitable means, and the disk 22 may be provided with several pairs of jaws or receptacles according to the speed at which it is driven relatively with the speed of the other parts of the 60 machine. Further, the disk or wheel 22 and the serrated wheel 2 of the magazine are each provided with a suitable brake not shown, for governing their movements.

The action of the apparatus is as follows:—At the commencement of operations

the paper sheet E is fed forward to the position shown at Fig. 2, by the rollers B C, the knife V then comes into operation and cuts off a portion which serves as a wrapper for the next article to be treated. The wheel 70 2 is now moved to feed said article to the chute 4 where it is temporarily held by the jaws 13. The plunger now descends and presses the article down on to the wrapper and against the plate 18 until both article 75 and wrapper are within a recess formed by the jaws 20 and 21 in the disk or wheel 22, the jaw 21 having been moved back against the spring 23 to allow of easy access. Before the plunger is withdrawn however the 80 jaw 21 is released, gripping the partially wrapped article and holding same during such withdrawal see Fig. 8, and later until it is dislodged from the machine a complete package. Immediately following the withdrawal of the plunger 14 one of the free sides of the wrapper is laid by the plate 26 see Fig. 9, and the other side by the plate J during the next operation of the disk 22 which is synonymous with the next feed of 85 the sheet for the next package. The article on the said next feed is brought opposite the twisting jaws 29 see Fig. 10, which operate to seize and twist the free ends of the wrapper to complete the package; meanwhile a second article has been introduced to the wrapping mechanism so that on the third feed operation the first article 90 completely wrapped or parcelled is released by the twisting jaws and the second package 100 brought into position for having its open ends twisted, while a third article is now introduced to the wrapping mechanism, and so on until during the twisting of the third package the first package is pressed out of 105 the disk 22 into a receptacle, conveyer or the like for removal. These operations are continued until as each article to be wrapped is introduced to the wrapping mechanism, a completed package is discharged therefrom, the output being limited by the 110 capacity of the apparatus or the speed at which it may be driven.

All the cams are arranged to operate upon the several levers at the proper time to insure an accurate, continuous and automatic performance of the operations necessary in wrapping or parceling toffee or other suitable goods.

The machine may be duplicated and operate in series, and may be rotated by means of driving belts, an electric motor or the like, and where desired or necessary appropriate clutch mechanism may be employed for governing the stopping and starting of the 125 rotary motion thereof.

In the apparatus above described where sweets or confectionery are being wrapped or parcelled it may be necessary that they should be fed to the magazine by hand o-

- ing to their sticky or adhesive nature; however when other articles such as spools or carriers for silk or somewhat similar goods are to be operated upon, then I may arrange 5 these to be automatically fed through a hopper, chute, or other device or to a disk or the like provided with appropriately shaped openings or serrations somewhat in the manner above referred to.
- 10 What I claim as may invention and desire to secure by Letters Patent is:—
1. In a wrapping machine and in combination, an intermittently rotated delivery magazine, an intermittently rotated parceling wheel having recesses with movable sides, an elbow lever for operating the movable sides, a main shaft and a cam on the main shaft for operating the elbow lever, a shaft supporting the parceling wheel, a 15 paper feeding means geared to and operable by the said shaft, a paper cutter upon a shaft oscillated by a lever actuated by operation of a cam on main shaft, a spring operated plunger, a back shaft, a cam on the back 20 shaft, an elbow lever controlling the spring plunger operated by said cam, frictionally held parcel supports and ejectors, a movable folder, an elbow lever operatively connected with the movable folder, a cam for operating 25 the last mentioned elbow lever, a stationary folder for positioning the cut wrapper, a twisting device comprising spring controlled gripping jaws, levers co-actuating with the jaws, cams for operating the 30 levers, means for simultaneously giving said jaws oscillating movement, and a movement longitudinal of their bearing, and a cam actuated elbow lever operating the ejectors 35 as described.
  2. In a wrapping machine of the class described, the combination with an intermittently rotating delivery magazine, paper feeding means, paper cutter and spring actuated plunger, of an intermittently rotated 40 parceling wheel having peripheral recesses provided with movable sides, an elbow lever, frictionally held parcel supports within the peripheral recesses in said wheel, the movable sides of said recesses being retracted to 45 receive the stack and its wrapper and released to hold the same during the wrapping 50 operation by the said elbow lever, a cam for operating the elbow lever, and means for intermittently rotating said wheel, the means 55 for supporting and folding the wrapper, the twisting grippers and means for opening same and for giving them an oscillating movement and a movement longitudinal of their bearing, as described.
  3. In a wrapping machine of the class described, a shaft supporting the parceling wheel, a paper feeding means geared to and operable by the said shaft, a shaft, a paper cutter upon said shaft, a lever oscillating 60 said shaft, a main shaft, a cam mounted thereon adapted to actuate said lever, a parceling wheel in which the peripheral recesses contain a frictionally held parcel support and movable sides, the means for retracting the movable sides against a spring to receive 65 the stock and wrapper and releasing the same to hold said stock during wrapping operation, and the means operating the parcel support to eject the wrapped article, as 70 described.
  4. In a wrapping machine of the class described, a vertical shaft carrying a sleeve, a delivery magazine comprising a notched or recessed plate intermittently rotatable within a fixed flanged disk, and a ratchet wheel 75 operating said plate whose teeth correspond in number with the recesses therein, a ratchet engaging said wheel, a back shaft driven from main shaft, a cam on said shaft, a spring controlled lever connected with 80 ratchet and actuated by the cam to move said ratchet and ratchet wheel, the space of one tooth each revolution of the cam shaft, as described.
  5. In a wrapping machine of the class described, a twisting device comprising spring controlled grippers, a parceling wheel, a shaft upon each side of parceling wheel and at right angles to same to which said grippers are pivotally connected, a main shaft, 90 a back shaft driven from said main shaft, spring actuated elbow levers and cams on the back shaft for operating said spring controlled elbow levers to open said grippers before and after each twisting operation and 100 means for giving said grippers oscillating movement, and a movement longitudinal of their bearing, as described.

In testimony whereof I have signed my name to this specification in the presence of 105 two subscribing witnesses.

HARRY BRADWELL.
